US00D887020S

(12) **United States Design Patent** (10) **Patent No.:** **US D887,020 S**
(45) **Date of Patent:** **** Jun. 9, 2020**

(54) **ANTI-FLOOD BARRIER**

(71) Applicant: **FLUVIAL INNOVATIONS LTD.**,
Poole, Dorset (GB)

(72) Inventor: **Simon Phelps**, Ferndown (GB)

(73) Assignee: **FLUVIAL INNOVATIONS LTD.**,
Poole, Dorset (GB)

(**) Term: **15 Years**

(21) Appl. No.: **29/658,384**

(22) Filed: **Jul. 31, 2018**

(51) LOC (12) Cl. **25-02**

(52) U.S. Cl.

USPC **D25/38.1; D10/113.3**

(58) **Field of Classification Search**

(57) **CLAIM**

The ornamental design for an anti-flood barrier, as shown and described.

DESCRIPTION

FIG. 1 is a top plan view of an anti-flood barrier showing my new design;

FIG. 2 is a top perspective view thereof;

FIG. 3 is a bottom perspective view thereof;

FIG. 4 is a right side elevational view thereof;

FIG. 5 is a left side elevational view thereof;

FIG. 6 is a front elevational view thereof;

FIG. 7 is a rear elevational view thereof;

FIG. 8 is a top plan view of a second embodiment for an anti-flood barrier;

FIG. 9 is a top perspective view of the second embodiment;

FIG. 10 is a bottom perspective view of the second embodiment;

FIG. 11 is a right side elevational view of the second embodiment;

FIG. 12 is a left side elevational view of the second embodiment;

FIG. 13 is a front elevational view of the second embodiment; and,

FIG. 14 is a rear elevational view of the second embodiment. The broken lines showing optional openings and an optional cushion in FIGS. 1-7 are environmental only and form no part of the claimed design.

1 Claim, 6 Drawing Sheets
